PHONOGRAPH APPARATUS

Emil I. Harman, Philadelphia, Pa., assignor, by
mesne assignments, to Philco Corporation,
Philadelphia, Pa., a corporation of Pennsyl-
vania

Application April 18, 1945, Serial No. 588,924

8 Claims. (Cl. 274—9)

1

This invention relates to phonographs and more specifically to a novel phonograph apparatus which is adapted to play records with a minimum of effort on the part of the operator.

It has been proposed heretofore to construct a phonograph in which the tone arm and the turntable driving means are controlled in response to manual movement of a member, so that the user has only to operate the said member and to insert and remove records. For example, in my copending application, No. 524,043, filed February 26, 1944, now Patent No. 2,475,744, issued July 12, 1949, there is disclosed a phonograph apparatus in which a drawer is opened to afford access to the mechanism, and the tone arm and turntable driving means are controlled in response to movement of the drawer. Other prior devices of this same general character have been proposed, in which a lid or the like affords access to the mechanism, and in which the tone arm and turntable driving means are controlled in response to movement of such member.

While such devices require little effort on the part of the user, they are subject to the objection that the operating parts are accessible and may be tampered with. Children especially are prone to tamper with the parts which are thus subject to possible damage. Moreover, no provision is made in some of these prior devices for the playing of different sized records, and in those instances in which there is such provision, it is necessary for the user to perform an additional manual operation in order to adapt the phonograph for the playing of records of a particular size.

One object of the present invention is to provide a novel phonograph apparatus in which the operating parts are not accessible, and in the use of which it is only necessary to insert and remove records through a door-closed restricted aperture of slot-like form, and to operate the door.

Another object of the invention is to provide a phonograph apparatus in which the operating parts are enclosed at all times within a housing or enclosure having a restricted opening for inserting and removing records, and the said parts are actuated from outside said housing by means of a manual control member which is preferably a door or lid adapted to conceal said opening.

Still another object of the invention is to provide a phonograph apparatus of this character in which the tone arm and the turntable driving means are controlled or actuated in response to the opening and closing movements of a door or lid associated with the record-insertion opening.

2

A further object of the invention is to provide a phonograph apparatus of the stated character which is adapted to play different sized records without any further effort on the part of the user.

5 This is accomplished by the provision of a novel "feeler" mechanism and stop arrangement which automatically limits the movement of the tone arm according to the size of the record inserted in the aforementioned opening.

10 A further object of the invention is to provide an arrangement, including the feeler mechanism and stop means adjustable thereby, for positioning an inserted record on the turntable.

15 Other objects and features of the invention will be apparent from the following detailed description in conjunction with the accompanying drawings in which:

Fig. 1 is a perspective view of a radio-phonograph combination embodying the invention;

20 Fig. 2 is a sectional view taken vertically through the same;

Fig. 3 is a horizontal sectional view showing the phonograph apparatus in plan;

25 Fig. 4 is a perspective view of a slide member which serves to actuate the parts as previously mentioned;

Fig. 5 is a fragmentary perspective view showing the cord and pulley arrangement employed;

30 Fig. 6 shows the phonograph apparatus in side elevation with the door in closed position, and with a small sized record on the turntable;

Fig. 7 is a sectional view taken along lines 7—7 of Fig. 3, showing the parts in the positions which they assume when the door is opened and a large size record is inserted;

35 Fig. 8 is a detailed sectional view showing more clearly the receding spindle arrangement which is preferably employed;

Fig. 9 is a fragmentary plan view of the feeler mechanism;

40 Fig. 10 is a fragmentary plan view showing the latch member of the same mechanism in a different position than that of Fig. 9;

Fig. 11 is a detail view of the switch mechanism which controls the turntable operation, said view being taken along line 11—11 of Fig. 3;

45 Fig. 12 is a view of the same mechanism taken from the left side of Fig. 11;

Fig. 13 is a plan view of the same mechanism;

50 Figs. 14 and 15 are explanatory views showing how the switch is operated;

Fig. 16 is a plan view similar to Fig. 3, showing a modified form of the "feeler" mechanism;

55 Fig. 17 is a fragmentary view of the latch

member in a different position than that of Fig. 16;

Fig. 18 is a vertical sectional view of another embodiment of the phonograph apparatus;

Fig. 19 is a fragmentary plan view, partly in section, showing certain parts of the feeler mechanism;

Fig. 20 is a detail sectional view taken along line 20—20 of Fig. 19;

Fig. 21 is a perspective view of the apparatus, showing the tone arm actuating mechanism in the course of operation;

Fig. 22 is a plan view of the operating mechanism which adapts the apparatus for the playing of different sized records;

Fig. 23 is a perspective view illustrating further the tone arm controlling mechanism;

Fig. 24 is a detail sectional view taken along line 24—24 of Fig. 23; and

Fig. 25 is an exploded view illustrating certain parts of the apparatus.

The apparatus first to be described not only embodies the novel features of the present invention but also embodies certain features and specific structures which are not claimed herein but are claimed in a copending application of E. O. Deaver, Serial No. 589,017, filed April 18, 1945, now U. S. Patent No. 2,485,575, and a copending application of E. O. Thompson, Serial No. 589,019, filed April 18, 1945.

Referring first to Figs. 1 and 2, the novel phonograph apparatus of the present invention is shown embodied in a radio-phonograph combination comprising a cabinet 1, radio receiver 2 and its associated dial 3 and control knobs 4, phonograph apparatus 5, and loudspeaker 6. The phonograph mechanism is supported by a horizontal shelf or panel 7 within the cabinet. The phonograph tone arm and turntable are shown at 8 and 9, respectively. In accordance with the present invention, the phonograph apparatus is inaccessible to the user, and provision is made for the playing of successive records simply by inserting them into a restricted slot-like opening 10 adjacent the turntable 9, and by operating a door associated with said opening. To this end, there is provided a front wall member 11 which forms a part of the cabinet structure and which has the record-insertion opening 10 therein. A record 12 is shown on the turntable, and it will be noted that the record protrudes from the opening 10 into a recess 13 provided in member 11. The purpose of this arrangement is to enable insertion and removal of the record as will be obvious. Adjacent the recess 13, and hingedly mounted on the outer part of the cabinet, is a manually operable door 14 which occupies the door opening 15 when in closed position. When closed, the door conceals the record-insertion opening 10, and when opened it affords access to the said opening. As previously mentioned, the movement of the door serves to control the tone arm and the turntable.

It will be apparent from Figs. 1 and 2, and from the description thus far, that the phonograph apparatus is fully protected against accidental misuse or abuse, there being no reason for access to the parts since the user is required only to operate the door 14 and to insert and remove records.

While the phonograph apparatus is shown in Figs. 1 and 2 as a part of a radio-phonograph combination, it need not be associated with a radio receiver, as will be well understood.

Referring now to Figs. 3 to 10, these figures

illustrate the mechanism by which the tone arm and turntable are controlled by the door 14, and they also illustrate the mechanism by which the apparatus is adapted to play different sized records without any further effort on the part of the user. As shown most clearly in Fig. 6, the turntable 9 is arranged in relation to the restricted opening 10 so that the upper surface of the turntable is slightly above the bottom surface of the opening. This permits the record 12 to rotate freely with the turntable. It will be noted also that the door 14 has a recess 14' to accommodate a larger sized record represented in dot and dash outline at 12'. A guide member 11' is secured to wall 11 and extends therefrom above the turntable as shown. This member may take the form of a strip or plate of metal or other material, and its purpose is to insure proper insertion of the record, as will be seen later. The record is centered on the turntable by means of a central spindle 16 (Fig. 7) which is automatically retracted in response to opening movement of the door 14, as will be described further hereinafter. As shown in Fig. 8, the turntable is supported by means of a bearing structure 17 carried by the supporting shelf or panel 7. The details of the bearing structure are unimportant except that it may be noted that the record-centering spindle 16 is slidably mounted within the same structure. The turntable is driven in conventional manner (see Fig. 3) by means of a driving friction wheel 18 which is mounted on a pivoted bracket 19 and is maintained in engagement with the turntable flange by a spring 20, one end of which is attached to the bracket 19 while the other end is secured to a stationary pin 21 on the supporting panel 7. The wheel 18 is driven by a smaller wheel or roller 22 which in turn is suitably driven by the driving motor unit 23.

The tone arm 8 is mounted at the upper end of a spindle 24 (see Fig. 6) which is rotatably supported by a hollow post 25 mounted on the supporting panel 7, so that the tone arm is adapted to move laterally or horizontally with respect to a record on the turntable. The tone arm is pivotally mounted on a horizontal pivot 8' so as to be vertically movable with respect to the record. At its free end the tone arm carries a suitable pick-up which may be of conventional form and which includes the usual needle or stylus 26. At the lower end of the tone arm-carrying spindle 24, there is provided an extending arm 27, the purpose of which is to actuate a switch mechanism 28 at the end of the playing of a record so as to automatically stop the rotation of the turntable, as will be further described hereinafter.

As previously mentioned the operating parts are controlled by the movements of the door 14. To this end, there is provided at the under side of the supporting panel 7 a slide member 29 (see Fig. 4), which is slidably supported by the supporting panel. Member 29 has slots 30 and 31 therein, by means of which it is slidably supported for rectilinear movement forwardly and rearwardly. As shown in Fig. 7, the supporting arrangement for the slide member 29 may include a pair of fastening elements, such as screws 32 and 33, which are carried by the supporting panel 7 and which extend through the slots 30 and 31 respectively. Thus it will be seen that the slide member 29 is supported for guided movement in the manner stated. At its forward end the slide member 29 has a depending lug 34 to which one end of a connecting link 35 is piv-

totally connected. The other end of link 35 is pivotally connected to the door 14 at a point 36 (see Fig. 6) offset from the hinge or pivot 37 of the door. When the door is opened, the link 35 is pulled forwardly so as to move the slide member 29 from the position of Fig. 6 to that of Fig. 7; and when the door is closed, the said parts are moved in the reverse direction so that the slide member 29 moves to the position of Fig. 6. An important feature of the apparatus provided by the present invention is the control of the various moving parts by a single movable member, in this instance the slide member 29, which is actuated by the door.

Referring to the actuation of the tone arm 8 by the movement of the slide member 29, while various means might be employed for this purpose, it is preferred to employ the mechanism now to be described which is claimed in the above-mentioned Deaver patent. As clearly shown in Fig. 6, there is provided at the rear of the tone arm 8 an extending lug 38 carrying a screw 39 to which one end of a flexible cord 40 is attached. The cord passes around a pair of pulleys 41 and 42, and its other end is attached to one end of a helical spring 43 whose other end is secured to a screw 44 carried by a depending lug 45 on the slide member 29. The pulleys 41 and 42 (see Fig. 5) are rotatably mounted on a bracket 46 secured to the under side of the supporting panel 7. The bracket 46 has cord guiding and retaining portions 41' and 42' as clearly shown in Fig. 5. The pulleys are so arranged that when a pull is exerted on the cord 40 by the forward movement of the slide member 29, the tone arm is subjected to both vertical and horizontal force components which lift the tone arm off of the record and swing it laterally to a position in which it may be lowered onto the next record. Furthermore, the horizontal pivot 8' of the tone arm is so arranged in relation to the vertical pivotal support that the vertical force component is effective to lift the needle or stylus off the record before the tone arm is moved laterally, thus preventing scratching of the record. When the slide member 29 is in its rearward position, i. e. when the door 14 is closed, there is no tension on the spring 43 and the tone arm is in its operative position. When the slide member is in its forward position, i. e. when the door 14 is open, the spring 43 is placed under tension and the tone arm is raised. The tension of the spring urges the tone arm laterally against a stop, as will be described further hereinafter.

As previously mentioned, the phonograph apparatus provided in accordance with the invention is adapted to condition itself automatically for the playing of different sized records. Since records are commonly made in two sizes, 10 inch and 12 inch respectively, the apparatus is preferably designed to play such records. This feature of the invention involves the provision of a "feeler" mechanism now to be described. Specific features of this mechanism are claimed in the above-mentioned Thompson application. As shown in Fig. 3, this mechanism may comprise a pair of L-shaped members 47 and 48 pivotally supported at the upper side of supporting panel 7 at points 49 and 50 respectively. These feeler members are arranged as shown and their inwardly extending arms 51 and 52 are pivotally connected together by a movable pin 53, as shown most clearly in Figs. 6 and 7. To permit free movement of the feeler members about pivots 49

and 50, the arms 51 and 52 may have slightly elongated openings for the pin 53, as shown in Fig. 9. The forwardly extending arms, 54 and 55 of the said feeler members are interconnected by means of a spring 56 which urges the said arms toward one another.

A stop 57 is arranged so as to be engageable by arm 54 and serves to limit the inward movement of the two arms. At their outer ends, each 10 of the forwardly extending arms 54 and 55 carries a roller 58 and 59 for engagement with an inserted record as hereinafter described.

The arm 55 also carries a post 60 which serves as a positioning or indexing means for the tone arm, so as to govern the record-commencing position of the tone arm according to the size of the record which it is desired to play in any instance. A covering 61 on the upper part of post 60 may be used to cushion the tone arm 20 when it engages the post.

As shown in Figs. 3 and 7 the connecting pin 53 for the feeler members 47 and 48 is movably mounted in a slot 62 provided in the supporting panel 7. At its lower end the pivot pin has a projection 63 which is engageable by a latch member 64 (see Figs. 9 and 10) which is pivotally carried at the underside of the supporting panel at 65. This latch member is shaped as illustrated and has a recess 66 into which the projection 63 may enter, as shown in Fig. 10. The latch member 64 also has a slot 67 through which a pin 68 on the slide member 29 extends. By means of this interconnection between the latch member 64 and the slide member 29, the former is rotated about the pivot 65 during movement of the slide member. The purpose of the structure just described will be apparent presently.

In Figs. 3 and 6 the record 12, shown in solid lines, is a small sized record, e. g. a 10 inch record. 40 Normally the feeler arms 54 and 55 are positioned in their innermost positions, as shown in Fig. 3, and the pin 53 is removed from the latch member 64. In this condition of the apparatus, the rollers 58 and 59 are spaced apart sufficiently so that a 10 inch record may be inserted between them without actuating the feeler mechanism, as may be seen in Fig. 3. When the record is in place on the turntable, the rollers are free of the edge of the record. The stop 57, which establishes the innermost position of the rollers, is eccentric in form and may be adjusted to provide the desired clearance between the rollers and the record.

55 When a larger sized record, e. g. a 12 inch record, is inserted, it engages the rollers 58 and 59 and moves the feeler arms outwardly as shown in dot and dash outline in Fig. 3, wherein the larger sized record is shown in dot and dash outline at 12'. At this time, the door 14 is necessarily open and the slide member 29 has moved forwardly so that the latch member 64 is in the position of Fig. 9. As the feeler arms move outwardly, the pin 53 moves forwardly in the slot 62, bringing the projection 63 of said pin into the position shown in Fig. 9. At this time, the feeler arms are being held in their outer position by the larger record 12', as shown by the solid line illustration in Fig. 9. When the door is closed, the slide member 29 moves the latch member 64 to the position of Fig. 10. The latch member thus latches the feeler arms in their outer position and it is also shaped so as to cam the pin projection 63 slightly forward and thereby move the feeler arms a little further outwardly so that the rollers

58 and 59 are free of the record 12', as shown by the broken line representation of the arm 54 in Fig. 9. When the door is opened, following the playing of the record, the latch member 64 is returned to the position of Fig. 9, and when the record 12' is removed, the feeler arms return to their inner positions. Thus, each time a larger sized record is inserted, the feeler arms are moved outwardly sufficiently to clear the record as soon as the door is closed, and when the door is opened the record is removed, the feeler arms return to their normal inner position.

One purpose of the feeler arm movement is to position the tone arm indexing post 60 so that the tone arm will be properly indexed for the different sized records. Normally the post 60 is positioned as shown in Fig. 3 so as to index the tone arm for the smaller sized records, but when a larger sized record is inserted, the indexing post is moved outwardly to a position in which it indexes the tone arm for the larger sized record.

As previously mentioned, provision is made in the apparatus under discussion for causing the record-centering spindle 16 to recede in response to opening movement of the door 14. This feature is claimed in the above-mentioned Thompson application. As shown in Figs. 7 and 8, the centering spindle is lowered from its operative position to an inoperative position, in which its upper end is flush with or slightly below the surface of the turntable 9. This withdrawal of the centering spindle facilitates insertion and removal of the records, and it permits the employment of a narrower record-insertion slot than would otherwise be permissible, since it permits the insertion and removal of records in a horizontal plane immediately above the turntable and does not require any tilting or inclination of the record. This will be seen more clearly from the subsequent description of another embodiment in which a stationary spindle is employed.

Referring to Figs. 7 and 8, the centering spindle 16 has its upper end tapered and it is carried by a rod 69 which is slidably mounted within the turntable bearing structure 17. At its lower end, the rod 69 carries a block 70 from one side of which projects a pin 71. The latter is disposed in a cam slot 72 (see Fig. 4) of a depending plate 73 formed integrally with the slide member 29. The cam slot 72 is so shaped that it lowers and raises the centering spindle 16 in response to opening and closing movements of the door 14. When the door is closed, the pin 71 is in the higher portion of the cam slot 72, as shown in Fig. 6, and the centering pin is in its operative position. When the door is opened, the forward movement of the cam slot 72 lowers the spindle 16 to its inoperative position, as shown in Fig. 7, at which time the pin 71 is in the lower part of the cam slot 72. When the door is again closed, the inclined portion of the cam slot 72 moves the spindle-carrying rod 69 upwardly to return the spindle 16 to its operative position.

When a record is inserted, at which time the door 14 is open and the centering spindle 16 is in inoperative position, the record is approximately centered on the turntable by the rollers 58 and 59 on feeler arms 54 and 55 and also by a rear stop structure now to be described. Referring to Figs. 3, 6 and 7, this rear stop structure comprises a stationary stop 74 mounted on the supporting panel 1 and a movable stop 75 pivotally mounted on the stationary stop at 76. Movable stop 75 is generally of U shape and has downwardly extending arms 77. The ends of these arms are

interconnected with the pin 53 which interconnects the arms 51 and 52 of the feeler mechanism, as previously described. To this end, the pin 53 has an upper projection 78, and a connecting element 79 serves to interconnect the arms 17 with the said upper projection of the pin 53. As illustrated, the element 79 may take the form of a piece of stiff wire or a bendable rod whose intermediate portion encircles the projection 78 and whose ends are secured to the arms 77. By means of this structure, the movable stop 75 is actuated in response to movement of the pivot pin 53.

When the feeler mechanism is in the normal position for the playing of smaller sized records, as previously described, the pin 53 is at the rear of slot 62 and the movable stop 75 is in operative position, as shown in Fig. 6, and serves to limit the movement of a record during insertion thereof. However, when the feeler mechanism is actuated by the insertion of a larger sized record, as previously described, the pin 53 moves forwardly in slot 62 and raises the stop 75 to an inoperative position, as shown in Fig. 7. The stationary stop 74 is then effective to limit the movement of the larger sized record as the latter is inserted. It should be noted that the movable stop 75 is raised before the edge of the record reaches the location of the stop structure.

By means of this arrangement, either sized record is approximately centered on the turntable, and when the center spindle 16 moves upward to its operative position, its tapered end enters the center hole of the record and the spindle centers the record exactly on the turntable.

Referring now to the switch mechanism hereinbefore mentioned, the purpose thereof is to automatically stop the turntable at the end of the playing of a record, and to control the rotation of the turntable in response to movement of the door 14. The switch mechanism per se is claimed in the above-mentioned Thompson application. The switch mechanism is shown in detail in Figs. 11 to 15 to which reference may now be had. This mechanism comprises an inverted U-shaped supporting bracket 80 secured to the underside of the supporting panel 1, the under surface of which is represented by the dot-and-dash horizontal line in Figs. 11 and 12. The bracket 80 carries a rotatable shaft 81 which is suitably journaled in bearings 82 and 83 which may form integral parts of the supporting bracket. A mercury switch 84 is carried by a supporting member 85 which is mounted on one end of the shaft 81 so as to be rotatable therewith. A pair of stops 86 and 87, formed integrally with the supporting bracket 80, serve to limit the movement of the switch-supporting member 85 as shown in Fig. 12. Member 85 extends upwardly from the axis of rotation and carries a pin 88 at its upper end, upon which an actuating element 89 is pivotally mounted. The pivot point is above the center of mass of element 89, so that the latter normally assumes a vertical position. The upper end of element 89 is provided with a friction hood 90 preferably formed of rubber or like material. The element 89 functions cooperatively with the previously mentioned arm 27 to actuate the switch mechanism at the end of the playing of a record, as will be described presently.

A resilient member 91, which may take the form of a piece of spring wire or the like, is secured to the bracket 80 at 92 and is wound about a supporting projection or finger 93 on the bracket 80, and has its lower end portion in frictional engagement with the shaft 81 so as to impose a

frictional drag on the shaft and thus tends to oppose rotation of the shaft. The purpose of this will appear presently. At the end of shaft 81 opposite the switch 84, there is provided a resilient finger 94 which is engageable by a cam member 95 (see Fig. 4) formed integrally with the slide member 29, the purpose of which will also appear presently.

Referring again to Fig. 3, the arm 27, which extends from the lower end of the tone arm-supporting spindle 24, has an enlarged end forming a plate 96 which is adapted to engage the friction hood 90, as shown in Figs. 14 and 15. The arm 27 is so positioned in relation to the tone arm 8 that the plate 96 engages the friction hood 90 when the needle or stylus engages the eccentric groove at the end of a record, the said groove being shown in Fig. 3 at 97. The eccentricity of the groove 97 may vary from one record to another, and the switch mechanism is designed to insure operation of the switch regardless of such variation.

The operation of the switch mechanism may best be explained with specific reference to Figs. 12 to 15. The mercury switch 84 is connected in circuit with the turntable driving motor so as to control the operation thereof, and during playing of a record, the switch is in the position of Figs. 12 and 14 in which it is closed, so that the turntable driving motor is energized.

Prior to the engagement of plate 96 with the friction hood 90, the element 89 is vertically positioned, as shown in Fig. 12, due to the fact that its supporting pin 88 is above its center of mass. As the needle or stylus approaches the eccentric groove at the end of the record, the plates 96, moving from left to right, as viewed in Figs. 12, 14 and 15, engages the friction hood 90 and deflects the element 89 to a position such as shown in Fig. 14. When the stylus enters the eccentric groove at the end of the record, the plate 96 moves back and forth, as indicated by the double head arrow in Figs. 14 and 15. The range of this oscillatory motion of the plate 96 is indicated by the dotted line representation in Fig. 13 and the associated double head arrow. Movement of the plate 96 toward the left in Figs. 14 and 15 causes application of a force to the pin 88 through the upper portion of element 89, which force moves the switch support 85 counterclockwise from the position of Fig. 14, as shown in Fig. 15. If the eccentricity of the record groove is relatively great, the first left-hand movement of plate 96 may move switch 84 sufficiently to open it. If the groove eccentricity is not so great, the element 89 is stepped progressively toward the left as shown in Fig. 15, thereby moving the switch progressively until it opens. Thus the switch is opened even though the eccentricity of the record groove may vary from one record to the next. The friction drag element 91 serves to maintain the switch in any position to which it is moved.

During the playing of a record, the cam member 95 is in the left hand position shown in Figs. 11 and 13. When the door 14 is opened, after the playing of a record, the cam member 95 moves to the right hand position shown in dotted outline in Figs. 11 and 13, and during such movement the upper surface of the inclined cam member engages the end portion of resilient finger 94. This would effect actuation of the switch mechanism to open the switch 84 if the switch had not already been opened by the action of the plate 96, as above described. Consequently, the resilient finger 94, being in a raised position, is engaged

by the upper part of cam member 95 and is deflected sufficiently to enable its end portion to ride over the upper part of the cam member as the latter moves to the right hand position shown.

When the door 14 is closed to initiate the playing of another record, the cam member 95 moves to the left hand position shown in Figs. 11 and 13. During this movement, the lower face of the inclined cam member engages the finger 94 and moves it downwardly, thus causing rotation of shaft 81 in a direction to close the switch 84 and thus energize the turntable driving motor. During this operation, the resilient finger 94 rides over the lower portion of the inclined cam member 95 to the position shown in Fig. 11.

Thus the cam member 95 functions, in response to movement of the door 14, to insure that the switch 84 is opened and to close the switch so as to start rotation of the turntable when the door is closed.

Considering the operation of the phonograph apparatus as a whole, let us assume that a record is being played, the door 14 being closed. At the end of the playing of the record, the switch mechanism 28 opens the switch 84 to stop the turntable in the manner just described. When the door 14 is opened to remove the record which has just been played and to insert a new record, the slide member 29 moves forwardly, and in doing so it performs several functions. It lifts the tone arm 8 off of the record and moves it to a starting position above the marginal portion of the record through the action of the cord and pulley arrangement, as hereinbefore described. It also moves the latch member 64 (Figs. 9 and 10) to an ineffective position. It also lowers the record centering spindle 16 to its inoperative position. It also insures that the motor switch 84 is opened.

The user may now remove the record which has just been played and insert a new record. Assuming that a smaller sized record is inserted, the feeler mechanism is not actuated but the other parts are actuated in response to closing movement of the door 14. During the insertion of the smaller sized record, the rollers 58 and 59 and the stop 75 serve to center the record approximately, as previously described. When the door 14 is closed, the rearward movement of slide member 29 raises the centering spindle 16, closes switch 84 to start rotation of the turntable, and lowers the tone arm to bring the stylus into engagement with the marginal portion of the record. The parts are so designed that these functions are performed in the order named. The spindle 16 exactly centers the record so that it is free of contact with the feeler rollers and the rear stop. The operating cycle is now repeated.

Suppose however, that a larger sized record is inserted. In such case the feeler mechanism is actuated, causing pin 53 to move forwardly in its slot 62 and thus moving the stop 75 to an inoperative position, as shown in Fig. 7. The approximate centering of the record is then effected by the stationary stop 74 in cooperation with the rollers 58 and 59. When the door 14 is closed, the pin 53 is latched in its forward position by the latch member 64 and is also cammed by the latch member sufficiently to disengage the rollers 58 and 59 from the edge of the record, as previously described with reference to Figs. 9 and 10. Aside from the operation of the feeler mechanism, the parts are actuated in the same manner regardless of the size of the inserted record.

While it has been assumed that the user desires to change records, as will usually be the

11

case, in some instances the user may desire to repeat the playing of a record. In such case he simply opens the door 14 and then closes it without changing records. The opening and closing movements of the door effect automatic operation of the parts to repeat the playing of the record, as will be obvious from the foregoing description.

It should be noted also that the playing of a record may be interrupted at any time merely by opening the door 14, in which case the cam member 95 will open switch 84 as hereinbefore described.

In Figs 16 and 17 there is shown a modification of the feeler mechanism, by means of which a possible objection of the previously-described mechanism is eliminated. In the apparatus hereinbefore described, the feeler arm rollers 58 and 59 (see Fig. 3) are disposed at the widest part of the record, and if the record should strike the rear stop with considerable force, the record might rebound outwardly and the center hole thereof might not be substantially aligned with the centering spindle. The modification of Figs. 16 and 17 prevents this from happening. As may be seen in Fig. 16 the feeler arms 54a and 55a (the latter carrying the tone arm positioning post 60a) are extended forwardly so that the rollers 58a and 59a are disposed forwardly beyond the widest portion of an inserted record. This arrangement prevents the record from rebounding as above-mentioned. In this instance, the feeler mechanism is actuated by both the smaller and larger sized records, and the latch member 64a is provided with two recesses 98 and 99 so as to latch the feeler arms in different positions for the different sized records. The different sized records are shown for comparison at 12 and 12'. If a smaller sized record is inserted, the feeler arms are inwardly disposed and the pin 53 is in the rearward end of its slot 62. Accordingly, the pin projection 63 enters recess 98 when the latch member 64a is moved to its operative position, and the feeler arms are latched and are also moved outwardly a slight amount to disengage the rollers from the record, by virtue of slight camming of the pin projection 63 as it moves into recess 99.

When a larger sized record is inserted, the feeler arms 54a and 55a are moved outwardly, causing the pin 53 to move to the forward end of its slot 62 in which it is positioned to enter the recess 98. When the latch member 64a is moved to its operative position, the feeler arms are latched and are moved outwardly a slight amount to disengage the rollers 58a and 59a from the record, by reason of the camming of the pin projection 63 as it moves in recess 98.

The modified feeler mechanism of Figs. 16 and 17 may be employed in the apparatus of the previous figures without changing the other parts, since such modification merely involves extension of the feeler arms and a different design of the latch member.

In Figs. 18 to 24 there is illustrated another embodiment of the phonograph apparatus embodying the features of the present invention. For the sake of simplicity, the housing or cabinet is not fully shown. Referring to Fig. 18, the front portion of the housing is shown at 100, with which there is associated a movable door or closure member 101 which is pivotally supported on brackets 102 secured to a mounting panel 103, the latter being fixedly mounted within the housing structure in any suitable manner. The hous-

12

ing or cabinet is provided with a slot-like record-insertion opening 104 to which access is had by moving the door 101 to the open position shown in Fig. 18. When the door is in its closed position, as indicated by the broken line representation in Fig. 18, it conceals the opening 104.

The record-supporting turntable 105 is rotatably mounted on the supporting panel 103 by means of a suitable bearing structure 106. The turntable may be driven by means of a driving motor unit 107 in conventional fashion. In this instance the record centering spindle 108 is stationary, and it is necessary to insert the record, shown at 109, in an inclined position. Consequently the slot 104 must be of greater depth than that provided in the previously described apparatus. The parts are so dimensioned that when a record is inserted in an inclined position, as shown in dot and dash outline in Fig. 18, the record clears the top of the spindle 108 and engages the rear portion of the turntable, so that the record may be slid inwardly until it engages a stop hereinafter described and then lowered into place.

The tone arm 110 is rigidly mounted at the upper end of a supporting spindle which is slidably and rotatably mounted within a hollow supporting post 111. The lower end of the tone arm supporting spindle is visible in Figs. 18, 21 and 23 and is designated 112. Extending laterally from the lower portion of the tone arm supporting spindle are arms 113 and 114 (see Fig. 23), the purpose of which is to effect and control movement of the tone arm as hereinafter described. At its free end the tone arm carries a suitable pick-up including the usual needle or stylus 115.

The tone arm is actuated and the rotation of the turntable is controlled by the movements of the door 101 through a link 116, one end of which is pivotally secured to the door structure at 117, and the other end of which is pivotally secured to a slide member 118 at 119 (see Figs. 21 and 23). The slide member 118 is slideably mounted on a depending stationary bracket 120 by means of pins 121 on the bracket and associated slots 122 in the slide member. This slide member has a flange 123 (see Fig. 18) which extends beneath the supporting bracket 120, and which carries a cam member 124 having an inclined surface 125. The flange and cam member are engaged by the lower end of the tone arm supporting spindle and serve to raise and lower the tone arm as the slide 118 moves forwardly and rearwardly in response to opening and closing of the door 101.

Adjacent the slide 118 is a second slide member 126 having slots 127 through which the pins 121 extend. This second slide member is urged forwardly by a spring 128 having one end secured to a lug 129 on the said slide member and having its other end secured to a lug 130 on the slide member 118. The forward movement of the second slide member 126 is limited by a pin 131 thereon which rides in a slot 131' in the first slide member 118.

The bracket 120 and the slide members 118 and 126 (see Fig. 25) have aligned openings therein, designated 132, 133, and 134 respectively, through which the arm 114 projects, as may be seen in Figs. 21 and 23. The opening in the slide member 126 is normally offset forwardly with respect to the opening in the adjacent slide member 118, as may be seen in Fig. 23. The purpose of the structure just described is to move the tone arm

laterally through the medium of arm 114 as will be seen more clearly later.

The slide member 118 also serves to operate a switch which controls the turntable driving motor. To this end, the slide member is provided with a projection 135 which is adapted to operate a push-button switch 135' (Figs. 18 and 25) which is mounted on bracket 129. The switch is normally closed, and when the slide 118 moves forwardly, as the door is opened, the projection 135 engages the switch and thus opens it. When the door is closed and the slide member moves rearwardly, the projection 135 moves away from the switch and the latter closes.

As in the previously described embodiment, provision is made for adjustment of the parts according to the size of the inserted record, by means of a feeler mechanism which is engageable by the record. This mechanism includes the mechanical linkages and parts shown in Fig. 22 which is a plan view of the parts immediately below the supporting panel 103, the latter being shown in dot and dash outline. At the front of the supporting panel there are provided a pair of L-shaped slides 136 and 137 having pins 138 and 139 which extend through slots 140 and 141, respectively, in the supporting panel 103. The two slides are urged toward one another by a spring 142 having its opposite ends secured to the slides at 143 and 144 respectively. Thus the two slides are movable in a horizontal plane parallel to the supporting panel 103 and they are normally maintained in inner positions by the spring 142.

Above the supporting panel 103 the outermost pins 138 and 139 carry plates 145 and 146 (Figs. 19 and 21) on which there are fixedly mounted feeler members 147 and 148 which are shaped to receive an inserted record. The feeler members have channels 149 and 150 for receiving a record and for guiding it inwardly, as shown in Fig. 18. The plates 145 and 146 carry latch members 151 and 152 each of which has a pivot, as shown at 153 in the left hand portion of Fig. 19, and an associated biasing spring 154. The latch members are adapted to cooperate with keepers in the form of lugs 155 and 156 turned up from the mounting panel 103. The latch members carry upstanding pins 157 and 158 which extend through arcuate slots 159 and 160 in the feeler members 147 and 148. As may be seen in Fig. 21, the pins 157 and 158 are disposed in the record-receiving channels 149 and 150 so as to be engageable by the edge of an inserted record. The purpose of this arrangement will be understood presently.

Referring again to Fig. 22 a lever 161 is pivotally secured to the supporting panel 103 at 162. At one end, the lever 161 carries a pin 163 which projects upwardly through an arcuate slot 164 in the panel 103. This pin serves as a rear stop for the inserted record, and it facilitates positioning of the record on the turntable. The lever 161 is moved to position the pin 163 by means of a link 165, one end of which is pivotally secured to the lever 161 at 166. The opposite end of link 165 is pivotally attached to links 167 and 168 by means of a connecting pin 169 which is supported and guided by a slot 170 in the supporting panel 103. Links 167 and 168 are pivotally connected to slides 136 and 137 at 171 and 172 respectively. The links 167 and 168 have a special purpose, as will be seen presently.

An arm 173 has one end pivotally supported by the tone arm supporting post and has a slot

174 at its opposite end through which one of the pins 139 extends. The purpose of arm 173 is to support certain elements which function cooperatively with the arm 113 (see Fig. 23) to govern the movement of the tone arm 110. Referring to Fig. 23, the arm 173 carries a depending finger 175 and it also carries a resiliently mounted detent member 176. The latter is mounted on a resilient plate 177 which is secured to arm 173 in spaced relation thereto by means of a supporting block 178. A screw 179 carried by arm 173 (see Fig. 24) extends through an opening in member 176 and serves as a support and stop therefor. The elements 175 and 176 are formed to provide a recess or space 180 (see Fig. 24) into which the end of arm 113 is adapted to enter.

Considering the operation of the apparatus, the latch members 151 and 152 are normally free of their respective keepers 155 and 156, the feeler members 147 and 148 being disposed in their inner positions shown in dot and dash outline in Fig. 19. The pin 163 is normally disposed in the forward portion of its slot 164 by reason of the disposition of the associated controlling mechanism. In such condition of the parts, if a smaller sized record (e. g. a 10 inch record) is inserted, the pins 157 and 158 merely serve in cooperation with pin 163 to facilitate the centering of the record.

For convenience of description it may be assumed that a smaller sized record is being played, the door 101 being closed and the slide members 118 and 126 being rearwardly disposed. As the stylus moves inwardly over the record, the arm 113 moves outwardly (see Fig. 23) adjacent to the extending portion of member 176. At the end of the playing of the record the user opens the door 101 which pulls the slide member 118 forward by exerting a pulling force on link 116. The slide member 126 also moves forwardly by virtue of its spring connection to slide member 118. As the slide member 118 moves forwardly the lower end 112 of the tone arm supporting spindle rides up the inclined cam surface 125, thus raising the tone arm so as to disengage the stylus 115 from the record. At the same time, the arm 113 is elevated. Meanwhile, the slide member 126 engages arm 118 and swings the tone arm outward, at the same time moving arm 113 inward toward the stop member 175. As the arm 113 approaches member 175 it engages the lower inclined edge of member 176 and raises the same slightly against the resilience of plate 177. When arm 113 engages the stop member 175, the arm disengages member 176 which snaps back to its normal position, so that the arm is then retained in the recess or space 180. The tone arm is then positioned above the marginal portion of the record ready to commence the playing of a new record.

In the meantime, the forward movement of the slide member 118 also opens the push-button switch for the turntable driving motor so as to deenergize the motor and stop the rotation of the turntable.

Having opened the door 101, the user removes the played record by tilting it sufficiently to disengage it from the centering pin and then pulling it outwardly through the slot opening 104, as may be seen clearly from Fig. 18. The user inserts a new record which enters the recesses 149 and 150 of the feeler members. Assuming first that the user inserts another smaller sized record, i. e. a 10 inch record, the peripheral edge of the record

will engage the pins 157 and 158 which cooperate with the rear pin 163 to guide the record into place on the turntable. During the insertion of the record, the feeler members 147 and 148 may be slightly deflected outward from their inner positions shown in dot and dash outline in Fig. 19, but such deflection is insufficient to cause latching of the latch members 151 and 152 which are disengaged from their keepers or detents 155 and 156. When the record is in place on the turntable, it is free of the pins and feeler members so that it is free to rotate.

When the user closes the door 101, the slide members 118 and 126 are moved rearwardly, thereby closing the switch for the turntable driving motor and lowering the tone arm to bring the stylus 115 into engagement with the marginal portion of the record. As the tone arm supporting spindle is lowered the arm 113 moves downward, as shown in Fig. 24 so that it is free of the detent member 176. The playing of the new record then commences, and the operating cycle is repeated.

Suppose now that the playing of a record has just finished, and that the user removes the record and inserts a larger sized record. As the larger sized record engages pins 157 and 158, it moves the feeler members 147 and 148 outward sufficiently to cause latch members 151 and 152 to engage their keepers 155 and 156, as shown in Fig. 19. The outward movement of members 136 and 137 (see Fig. 22) actuates lever 161 clockwise about its pivot 162, through the action of links 165, 167 and 168, thereby moving the pin 163 to a new position corresponding to the larger sized record. At the same time the arm 113 is moved counterclockwise about its pivot. Since the arm 113 (Fig. 23) is then retained by members 175 and 176 this arm is also moved counterclockwise, causing the tone arm to move outward to a new position for the commencement of the larger sized record. When the record is in place on the turntable, it is free of the pins and feeler members.

When the record is removed after the playing thereof, it engages pins 157 and 158 and deflects the latch members 151 and 152 and disengages them from the keepers or detents 155 and 156, whereupon the feeler members 147 and 148 move to their inner positions. The apparatus is then ready to receive a new record of either size.

The reason for the auxiliary slide member 126 will now be more clearly seen. The range of movement of the slide member 118 is fixed, since it corresponds to the movement of the door 101. On the other hand, the range of horizontal movement of the tone arm varies according to the different sized records. The auxiliary slide member 126 compensates for this difference between the ranges of movement of said parts.

As stated previously, the links 167 and 168 (Fig. 22) have a special purpose. These links not only form a part of the mechanism which positions pin 163 and arm 113 according to the size of an inserted record, but they also prevent improper operation of the said mechanism in the event that a smaller sized record is pushed against one of the feeler members 147 or 148 with considerable force. Due to the employment of the two links, the mechanism cannot be operated, by pressure on one feeler member, sufficiently to latch in the position for a larger sized record. Thus, the employment of the two links prevents improper operation of the mechanism by a smaller sized record as above mentioned.

It is to be noted further that pins 157 and 158

and the feeler members 147 and 148 are disposed forwardly of the widest portion of an inserted record, and therefore these elements prevent rebounding of a record as previously described with reference to Figs. 16 and 17.

The invention has now been fully described with reference to the illustrated embodiments. It will be understood, of course, that the invention is not limited to the specific forms shown but is capable of various modifications within the scope of the appended claims.

I claim:

1. In a phonograph apparatus, an enclosure having a restricted opening through which centrally-apertured disk records may be inserted and removed, a record-supporting turntable arranged within said enclosure to receive an inserted record, a record-centering pin located centrally of said turntable for engagement with the central aperture of a record, a pick-up device arranged within said enclosure for movement into and out of engagement with a record on the turntable, manually-operable means for moving said pick-up device from a record-finishing position to a record-commencing position, adjustable stop means for controlling the record-commencing position of said pick-up device according to the size of an inserted record, adjustable record stop means for limiting the insertion of a record according to the size thereof, a feeler mechanism operatively interconnected with both of the aforementioned stop means to adjust them according to the size of an inserted record, said feeler mechanism including a pair of feeler members cooperative with said record stop means to guide and to arrest an inserted record for engagement by said pin, means normally locating said feeler members and said record stop means radially from the center of said turntable at a distance slightly greater than the radius of a smaller sized record, said pin upon engagement with a smaller sized record serving to center such record and disengage it from said feeler members and from said record stop means, said feeler members being movable by an inserted larger sized record to adjust the two stop means, and means for latching said feeler mechanism, with said feeler members and said record stop means in positions to be free of the larger sized record, when such record is centered on the turntable by said pin.

2. In a phonograph apparatus, an enclosure having a restricted opening through which centrally-apertured disk records may be inserted and removed, a record-supporting turntable arranged within said enclosure to receive an inserted record, a record-centering pin located centrally of said turntable for engagement with the central aperture of a record, a tone arm mounted within said enclosure for record-playing movement in cooperation with said turntable, manually-operable means for moving said tone arm from a record-finishing position to a record-commencing position, an adjustable stop for controlling the record-commencing position of said tone arm according to the size of an inserted record, adjustable record stop means for limiting the insertion of a record according to the size thereof, a feeler mechanism operatively interconnected with said stop and said stop means to adjust them according to the size of an inserted record, said feeler mechanism including a pair of feeler members cooperative with said record stop means to guide and to arrest an inserted record for engagement by said pin, means normally locating said feeler members and said record stop means radially

from the center of said turntable at a distance slightly greater than the radius of a smaller sized record, said pin upon engagement with a smaller sized record serving to center such record and disengage it from said feeler members and from said record stop means, said feeler members being movable by an inserted larger sized record to adjust said stop and said stop means, and means for latching said feeler mechanism, with said feeler members and said record stop means in positions to be free of the larger sized record, when such record is centered on the turntable by said pin.

3. In a phonograph apparatus, an enclosure having a restricted opening through which records may be inserted and removed, a record-supporting turntable arranged within said enclosure to receive an inserted record, a record-centering pin associated with said turntable, a pick-up device arranged within said enclosure for movement into and out of engagement with a record on the turntable, a hinged door on said enclosure adapted to conceal said opening when in closed position, means operable by said door for moving said pick-up device from a record-finishing position to a record-commencing position, adjustable stop means for controlling the record-commencing position of said pick-up device according to the size of an inserted record, adjustable record stop means for limiting the insertion of a record according to the size thereof, a feeler mechanism operatively interconnected with both of the aforementioned stop means to adjust them according to the size of an inserted record, said feeler mechanism including a pair of feeler members cooperative with said record stop means to guide and to arrest an inserted record for engagement by said pin, said pin upon engagement with a smaller sized record serving to disengage, such record from said feeler members and from said record stop means, said feeler members being movable by an inserted larger sized record to adjust the two stop means, and means for latching said feeler mechanism, with said feeler members and said record stop means in positions to be free of the larger sized record, when such record is centered on the turntable by said pin.

4. In a phonograph apparatus, an enclosure having a restricted opening through which records may be inserted and removed, a record-supporting turntable arranged within said enclosure to receive an inserted record, a record-centering pin associated with said turntable, a tone arm mounted within said enclosure for record-playing movement in cooperation with said turntable, a hinged door on said enclosure adapted to conceal said opening when in closed position, means operable by said door for moving said tone arm from a record-finishing position to a record-commencing position, an adjustable stop for controlling the record-commencing position of said tone arm according to the size of an inserted record, adjustable record stop means for limiting the insertion of a record according to the size thereof, a feeler mechanism operatively interconnected with said stop and said stop means to adjust them according to the size of an inserted record, said feeler mechanism including a pair of feeler members cooperative with said record stop means to guide and to arrest an inserted record for engagement by said pin, said pin upon engagement with a smaller sized record serving to disengage such record from said feeler members and from said record stop means, said feeler

members being movable by an inserted larger sized record to adjust said stop and said stop means, and means for latching said feeler mechanism, with said feeler members and said record stop means in positions to be free of the larger sized record, when such record is centered on the turntable by said pin.

5. In a phonograph apparatus, an enclosure having a restricted opening through which records may be inserted and removed, a record-supporting turntable arranged within said enclosure to receive an inserted record, a record-centering pin associated with said turntable, driving means for said turntable, a pick-up device arranged within said enclosure for movement into and out of engagement with a record on the turntable, a hinged door on said enclosure adapted to conceal said opening when in closed position, means operable by said door for moving said pick-up device from a record-finishing position to a record-commencing position, means operable by said door for controlling said driving means so as to cause operation thereof only when said door is closed, adjustable stop means for controlling the record-commencing position of said pick-up device according to the size of an inserted record, adjustable record stop means for limiting the insertion of a record according to the size thereof, a feeler mechanism operatively interconnected with both of the aforementioned stop means to adjust them according to the size of an inserted record, said feeler mechanism including a pair of feeler members cooperative with said record stop means to guide and to arrest an inserted record for engagement by said pin, said pin upon engagement with a smaller sized record serving to disengage such record from said feeler members and from said record stop means, said feeler members being movable by an inserted larger sized record to adjust the two stop means, and means for latching said feeler mechanism, with said feeler members and said record stop means in positions to be free of the larger sized record, when such record is centered on the turntable by said pin.

6. In a phonograph apparatus, an enclosure having a restricted opening through which centrally-apertured disk records may be inserted and removed, a record-supporting turntable arranged within said enclosure to receive an inserted record, a record-centering pin located centrally of said turntable for engagement with the central aperture of a record, a tone arm mounted within said enclosure for record-playing movement in cooperation with said turntable, manually-operable means for moving said tone arm from a record-finishing position to a record-commencing position, an adjustable tone arm stop for controlling the record-commencing position of said tone arm, adjustable record stop means for limiting the insertion of a record, a pair of feeler members cooperative with said record stop means to guide an inserted record into position on said turntable for engagement by said pin, mechanism providing mechanical interconnection between said feeler members, said tone arm stop and said record stop means, means normally locating said feeler members and said record stop means radially from the center of said turntable at a distance slightly greater than the radius of a smaller sized record, said pin upon engagement with a smaller sized record serving to center such record and

disengage it from said feeler members and from said record stop means, and means for latching said feeler members and said record stop means in positions free of a larger sized record when such a record is centered on the turntable by said pin.

7. In a phonograph apparatus, an enclosure having a restricted opening through which records may be inserted and removed, a record-supporting turntable arranged within said enclosure to receive an inserted record, a tone arm mounted within said enclosure for record-playing movement in cooperation with said turntable, a hinged door on said enclosure adapted to conceal said opening when in closed position, means operable by said door for moving said tone arm from a record-finishing position to a record-commencing position, an adjustable tone arm stop for controlling the record-commencing position of said tone arm, adjustable record stop means for limiting the insertion of a record, a pair of feeler members cooperative with said record stop means to guide an inserted record into position on said turntable, and mechanism providing mechanical interconnection between said feeler members, said tone arm stop and said record stop means, whereby said feeler members serve additionally to control the adjustment of said tone arm stop and said record stop means.

8. In a phonograph apparatus, an enclosure having a restricted opening through which records may be inserted and removed, a record-supporting turntable arranged within said enclosure to receive an inserted record, a record-centering pin associated with said turntable, a tone arm mounted within said enclosure for record-playing movement in cooperation with said turntable, a hinged door on said enclosure adapted to conceal said opening when in closed position, means

operable by said door for moving said tone arm from a record-finishing position to a record-commencing position, an adjustable tone arm stop for controlling the record-commencing position of said tone arm, adjustable record stop means for limiting the insertion of a record, a pair of feeler members cooperative with said record stop means to guide an inserted record into position on said turntable for engagement by said pin, mechanism providing mechanical interconnection between said feeler members, said tone arm stop and said record stop means, whereby said feeler members serve additionally to control the adjustment of said tone arm stop and said record stop means, said pin upon engagement with a smaller sized record serving to disengage such record from said feeler members and from said record stop means, and means for latching said feeler members and said record stop means in positions free of a larger sized record when such a record is centered on the turntable by said pin.
